UNITED STATES PATENT OFFICE.

CLINTON SHAVER, OF UPPER SANDUSKY, OHIO.

ACETYLENE-GAS GENERATOR.

1,025,723.

Specification of Letters Patent.

Patented May 7, 1912.

Application filed September 6, 1910. Serial No. 580,611.

To all whom it may concern:

Be it known that I, CLINTON SHAVER, a citizen of the United States, residing at Upper Sandusky, in the county of Wyandot and State of Ohio, have invented a new and useful Acetylene-Gas Generator, of which the following is a specification.

My invention relates to improvements in acetylene gas generators, and has for its object the provision of a simple and inexpensive generator which will be free of complicated parts and may be cleaned readily by unskilled persons.

One object of the invention is to provide a simple and efficient mechanism by which a measured quantity of carbid will be fed to the generator as the supply of gas is consumed so that the requisite pressure in the service pipes will be automatically maintained.

The invention also has for its object the provision of simple means by which the loss of carbid will be prevented and the flow of the same when a charge is being delivered to the generator will be automatically arrested.

These stated objects, and such other incidental objects as will hereinafter appear, are attained in the use of the mechanism illustrated in the accompanying drawings, and the invention consists in certain novel features of the same which will be herein-after first fully described and then more particularly pointed out in the appended claims.

In the drawings,—Figure 1 is a central vertical section of a generator embodying my improvements. Fig. 2 is a detail vertical section taken centrally through the carbide holder at a right angle to the plane of the section shown in Fig. 1. Fig. 3 is an enlarged detail sectional view showing the carbide dumping mechanism arranged to receive a charge. Fig. 4 is a similar view showing the mechanism in the position assumed when delivering a charge to the generator. Fig. 5 is a detail perspective view of the dumping bucket or valve.

My improved generator comprises two tanks, 1 and 2, which may be supported upon any convenient form of base and, in the drawings, are shown as resting upon the lower ends of their walls with their bottoms arranged some distance above said lower ends. The tank 1 is the generating tank and is provided with an inner cylinder or

wall 4 rising from its bottom 3 concentric with and spaced from its outer wall and terminating below the upper end of the said outer wall. A cylinder or inverted cap 5 is arranged within the tank 1 with its open lower end inserted in the space between the inner and outer walls of the said tank and extending a considerable distance below the upper end of the inner wall, as clearly shown. This cap is secured in fixed relation to the tank by means of brackets or arms 6 secured at intervals to the upper closed end or top 7 of the cap and projecting outwardly therefrom to engage posts 8 rising from the outer wall of the tank.

A carbide holder or hopper 9 is secured in the upper end or top of the cap 5 and has its upper end closed by a plug or other closure 10 whereby the carbide placed within the hopper may be protected from the influence of the atmosphere. The lower end of the hopper or holder 9 is open, as indicated at 11, and extends a short distance into the top of the cap 5. From one side of the lower end of the hopper, a shield or cover plate 12 depends, and this shield or cover plate is formed on an arc struck with the pivot 13 of the dumping bucket or valve as a center. An apron 14 is secured in the lower end of the hopper and extends partly across the same, as clearly shown, while at the side of the hopper opposite the said apron, a swinging valve or closure 15 is hinged, as shown at 16, and this valve or cut-off plate is of such dimensions as to extend in its closed position to the edge of the apron 14 whereby the passage of the carbide from the hopper will be prevented, as will be readily understood on reference to Figs. 1 and 4.

The dumping valve or bucket consists of a body mounted to swing freely on the pivot pin 13 and provided with upstanding substantially parallel side walls or flanges 17 adapted to project above the lower extremity of the hopper and fit against the sides of the same so as to prevent loss of the carbide and also guide the dumping valve in its movements so that the delivery of a measured charge to the generating tank will be assured. The pivot pin 13 is secured in and extends between guards 18 secured to the under side of the top 7 of the cap, and these guards are each of greater area than and fit closely against the respective side walls or flanges 17 of the dumping valve and extend beyond the edges of the same, as shown

clearly in Figs. 2, 3 and 4, whereby the valve will be held in proper relation to the hopper, and the flanges 17 and guards 18 coact to prevent loss of the carbid and overcharging of the tank, by reason of the carbid spilling or sifting laterally over the sides of the hopper or the valve.

The body of the dumping valve or bucket is provided in its upper portion with two faces 19 and 20 arranged at an angle to each other and extending to the surface of the body whereby a pocket is formed adapted to receive the carbid from the hopper and hold the same until such time as the valve is tilted upon the pivot 13 to the position shown in Fig. 4, whereupon the carbid will be discharged into the water in the generating tank. The surface of the body between the side walls or flanges 17 and beyond the face 20 is curved, as shown at 21, concentric with the pivot 13, and is adapted to fit snugly against the plate 12, as shown in Fig. 3, whereby the accidental delivery of carbid over the edge of the valve will be prevented. The surface of the dumping bucket or valve in rear of the face 19 is also curved, as shown at 22, so that the said surface may ride easily under the cut-off valve 15 as the bucket is oscillated, whereby in the dumping position of the bucket, shown in Fig. 4, the cut-off valve will be swung upward so as to bring its edge close to the edge of the apron 14 and thereby prevent further flow of the carbid until the bucket has been swung in the reverse direction far enough to permit the edge of the face 19 to clear the edge of the cut-off valve 15, whereupon the said valve will drop into the pocket and permit carbid to flow from the hopper into the pocket, as will be readily understood on reference to Fig. 3.

The bucket is provided with a central perforated lug or arm 23 in rear of the pocket formed by the faces 19 and 20, and to the said lug is pivotally connected the upper end of a link 24. This link 24 extends downward within the generating tank to a point below a sheathing tube 25 secured in and depending from the top 7 of the cap 5 and it is then extended upward through the said tube in a branch 26 having its upper end pivoted to one end of a lever 27 which is fulcrumed on a post or bracket 28 secured to and rising from the tanks 1 and 2. The end 55 of the lever 27, opposite to the end connected with the link 26, has a pin and slot engagement with a stem 29 rising from the gasometer bell 30 which is arranged concentrically within the holding tank 2, as clearly shown. It will be readily seen that as the pressure of the gas within the tank 2 increases, the bell will rise and, consequently, cause the lever 27 to rock upon its fulcrum and thereby move the links 24 and 26 downward within the generating tank. A down-

ward pull will, consequently, be exerted upon the lug 23 so that the dumping bucket will be tilted to the position shown in Fig. 3, in which it will receive a fresh supply or charge of carbid. As the gas is consumed the weight of the bell will, of course, cause it to descend, and the lever 27 will then be rocked in the opposite direction so that the dumping bucket will be turned to the position shown in Fig. 4 and the charge of carbid in the bucket will be delivered to the water in the generating tank.

The tanks are filled with water to a point above the upper end of the inner wall 4 of the generating tank so that a perfect water seal will be formed around the cap 5 and the gasometer bell to prevent the escape of gas around the same, as will be readily understood. A gas pipe 31 has its open upper end arranged above the water level in the generating tank, and the said pipe extends through the bottom of the generating tank across to a point below the bottom of the holding tank and then up within the said tank and the bell whereby the gas generated within the tank 1 will be permitted to escape into the space above the water level in the bell where it may collect. This gas pipe is provided with a check valve 32 which will permit the gas to flow into the gasometer or holding tank, but will prevent its flow in the reverse direction so that it cannot return to the generating tank. A service pipe 33 leads from the space below the top of the gasometer bell through the bottom of the holding tank, and a branch 34 of this pipe leads to the point of consumption. The branch 34 is connected to the service pipe by a coupling 35, and from the side of the said coupling opposite the service pipe, pipes 36 and 33 lead into the generating tank where the pipe 33 communicates with the pipe 31 through a coupling 37. A water seal or trap 38 is provided between the pipes 33 and 36 so as to normally prevent the flow of gas through said pipes. The gas flowing through the pipe 31 and valve 32 frequently carries more or less solid matter with it and this together with impurities in the gas often corrodes or chokes the valve 32 so that it may at times fail to open and then an excess pressure of gas is generated within the cap 5, whereby the gas pressure within the generator exceeds the normal and may prove disastrous to the structure. Under these circumstances the water seal 38 will yield to permit flow of gas into the bell or expansion chamber whereby the pipe 33 together with the water seal operates as a safety device without, however, any waste of the generated gas.

It will be readily seen that I have produced a generator which is exceedingly simple in its construction and the arrange-

ment of its parts so that there is no complicated mechanism which is liable to get out of order, and a measured charge of carbid will be delivered to the body of water in the generating tank as the gas is used so that only so much gas will be produced as is necessary to maintain the supply. The arrangement of the side flanges 17 of the dumping bucket, the guards 18, and the 5 shield 12 effectually prevent the moisture within the generating tank reaching the supply of carbid within the hopper so that deterioration of the said supply will be prevented. The device is entirely automatic 10 in its operation and the carbid is retained within the hopper until the gasometer bell rises under the pressure of the generated gas. The dumping bucket will then be turned sufficiently to permit the cut-off 15 valve in the hopper to drop so that a quantity of the carbid sufficient to fill the pocket in the dumping bucket may escape therefrom. At this time, however, the bucket is in such a position that no carbid can escape 20 from any portion of the same into the water and, consequently, there will be no over production of the gas. As the pressure of the gas diminishes and the gasometer bell falls, the bucket will be tilted to the 25 position shown in Fig. 4, and the charge of carbid previously delivered thereto will be discharged into the water in the generating tank. At this time the curved surface 22 of the dumping bucket will be bearing against 30 the cut-off valve 15 so that the said valve will be forced up into the end of the hopper and, consequently, there will be no escape 35 of carbid from the hopper, and an overcharge of the generator cannot occur.

40 To clean the apparatus, it is necessary merely to lift the cap and the ball from their respective tanks to obtain access to all the parts. The removal of the pin or screw connecting the lever 27 with the stem 45 permits the bell to be lifted from the holding tank and pins 39 which hold the cap to the generating tank may be easily removed from the posts 8 to permit the cap to be lifted.

50 As the connecting pipes are below the bottoms of the tanks, stoppages or leaks therein may be repaired without dismantling the entire apparatus.

55 While I have described the principle of operation of the invention, together with the apparatus which I now consider to be the best embodiment thereof, I desire to have it understood that the apparatus shown is merely illustrative, and that such changes 60 may be made as are within the scope of the claims appended hereto.

Having thus described my invention, what I claim is:

1. In an acetylene gas generator, a generating tank, a hopper in the upper end of

the generating tank, a cut off valve in the lower end of the hopper mounted to turn upon an axis adjacent one edge of the valve, a rockable dumping bucket within the tank below the hopper provided with a portion positioned to underride the valve to move it into full closed position with relation to the hopper, and means for rocking the dumping bucket. 70

2. In an acetylene gas generator, a generating tank, a hopper thereon, a swinging cut off valve in the lower end of the hopper, a tiltable bucket below the hopper and provided with a curved portion adapted to engage the swinging cut off valve to move the same to the closed position, and means for tilting the bucket in one direction to release the cut off valve to discharge a measured charge from the hopper into the bucket and for moving the bucket in the other direction 80 to discharge said bucket into the generating tank and simultaneously close the valve. 85

3. The combination of a generator tank, a hopper in the upper end of the same, an apron extending partly across the lower end 90 of the hopper, a shield depending from the hopper adjacent the said apron, a cut-off valve in the lower end of the hopper adapted to extend to the said apron, a tiltable bucket mounted below the hopper and having a curved portion bearing against the shield, a second curved portion bearing against the cut-off valve, and a pocket between the two said curved portions adapted to receive a charge from the hopper, and 95 means for automatically tilting the said bucket. 100

4. The combination of a generator tank, a hopper in the upper end of the same, an apron extending partly across the lower end 105 of the hopper, a shield depending from the hopper adjacent the said apron, a cut-off valve in the lower end of the hopper adapted to extend to the said apron, guards below the hopper at opposite sides of the same 110 and the shield depending therefrom, a tiltable bucket mounted below the hopper between said guards and having a curved portion bearing against the cut-off valve, and a pocket between the two said curved portions adapted to receive a charge from the hopper, and means for automatically tilting the said bucket. 115

5. The combination of a generator tank, a hopper in the upper end of the same, an apron extending partly across the lower end 120 of the hopper, a shield depending from the hopper adjacent the said apron, a cut-off valve in the lower end of the hopper adapted to extend to the said apron, guards below the hopper at opposite sides of the same and the shield depending therefrom, a tiltable bucket mounted below the hopper between 125 said guards and having a curved portion bearing against the cut-off valve, and a 130

5 pocket between the two said curved portions adapted to receive a charge from the hopper, the bucket being further provided with side flanges extending upward beyond the ends of the pocket and the lower end of the hopper and bearing against the sides of the hopper between the guards, and means for automatically tilting the said bucket.

In testimony, that I claim the foregoing as my own, I have hereto affixed my signature in the presence of two witnesses.

CLINTON SHAVER.
